UNITED STATES PATENT OFFICE.

JOHN DYMOCK, OF STOCKPORT, ENGLAND.

TWINE.

1,038,490.

Specification of Letters Patent. Patented Sept. 10, 1912.

Original application filed October 7, 1909, Serial No. 521,538. Divided and this application filed August 22, 1911. Serial No. 645,450.

To all whom it may concern:

Be it known that I, JOHN DYMOCK, a subject of the King of Great Britain, residing at Stockport, in the county of Chester and 5 Kingdom of Great Britain, have invented certain new and useful Improvements in Twine; and I do hereby declare the following to be a full, clear, and exact description of the invention, such as will enable others 10 skilled in the art to which it appertains to make and use the same.

This invention relates to improvements in that class of twine which consists of a fibrous core and a paper covering and the object of 15 the invention is to render such twine much stronger than hitherto has been the case.

This application is a division of application Serial No. 521538, filed October 7th, 1909.

20 I attain this object by the twine formed as illustrated in annexed drawing.

b is the fibrous core and a the paper covering, the former being made of such as cotton, jute, hemp, flax or the like fibrous 25 material and the latter consisting of the ribbon of paper.

Instead of simply wrapping the paper ribbon a around the core b with edges to overlap parallel with the core and then twisting the two as hitherto, according to 30 this invention, the paper ribbon a is curled around the core b with edges opposite each other turned inwardly before the twist is imparted to the paper ribbon and core. This 35 inward turning of the edges of the paper ribbon causes the paper ribbon to become double at the edges which greatly strengthens the twine.

I claim:

As a new article of manufacture, twine 40 consisting of a textile fiber core and a paper ribbon curled around the said core with edges longitudinally opposite each other turned inwardly.

In testimony whereof I have affixed my 45 signature in presence of two witnesses.

JOHN DYMOCK.
